UNITED STATES PATENT OFFICE.

WILLIAM F.R. KLING, OF BROOKLYN, NEW YORK.

MECHANICAL FOUNTAIN.

Application filed July 8, 1921. Serial No. 433,350.

To all whom it may concern:

Be it known that I, WILLIAM FREDERICK KLING, a citizen of the United States, and a resident of the city of New York, borough 5 of Brooklyn, in the county of Kings and State of New York, have invented a new and Improved Mechanical Fountain, of which the following is a full, clear, and exact description.

10 This invention relates to a mechanical fountain.

Prior to this invention the usual practice in constructing mechanical fountains was to make use of the cone-shaped axle about 15 which the tanks revolve. Provided in this cone-shaped axle were a number of ducts which had to be drilled at certain angles so that they would register with the openings leading from the tanks, reservoir and 20 discharge pipe. The construction of this cone-shaped axle required considerable difficult machine work, thus increasing the manufacturing cost.

The object of this invention is to provide 25 a cheap and efficient mechanical fountain, with parts that are easy to be machined, having the reservoir placed on top and which may be operated to throw a jet of water above the water level in the reservoir by rotating a plurality of tanks.

This object is accomplished by providing 30 in conjunction with a reservoir a plurality of tanks rotatably mounted and means for alternately connecting them with the reservoir and discharge pipe to obtain a pressure in the discharge pipe equal to the 35 pressure of the water in the reservoir plus the head of water in one tank minus the friction losses.

40 This and other objects of the invention will be more clearly understood from the following detailed description and accompanying drawings.

Figure 1 is a top plan view of the fountain;

Figure 2 is a side elevation of the fountain showing the tanks;

Figure 3 is a vertical section taken through the tanks, bearings and hub;

50 Figure 4 is a vertical cross section taken through the bearing along the line 4-4, Figure 3;

Figure 5 is a vertical cross section along the line 5-5, Figure 3;

55 Figure 6 is a cross section through the hub along the line 6-6, Figure 3;

Figure 7 is a vertical section through the bearing along the line 7-7, Figure 3.

Referring to the above-mentioned drawings, the invention includes a frame constructed from a plurality of legs 16, a reservoir plate 17 mounted on the upper ends of the legs, and a plurality of bracing members 18. Positioned on the reservoir plate 17 is a reservoir 15 for holding a quantity 60 of liquid. Mounted on the bracing members 18 are boxes 21 and 22 carrying bearing members 19 and 20, the latter being fixed in position by bolts 23 and 24, respectively. Chambers 53 and 54 are provided 65 in the boxes 21 and 22. Mounted in the box 21 communicating with the chamber 53 and the reservoir 15 is a vertical pipe 56. A discharge pipe 57 communicating with the chamber 54 is carried by the box 70 22, the upper end 58 of the discharge pipe 75 extending up through the center of the reservoir 15.

An opening 27 is provided in the bearing 20 and communicates with the chamber 54. Formed in the bearing 19 is an opening 28 80 communicating with the chamber 53 and a by-pass 30 from which two openings 31 and 32 lead inward away from the chamber 53. Formed on the bearings 19 and 20 85 respectively, are shoulders 25 and 26. A cylindrical hub 29 fits over the bearing members 19 and 20 and is retained in position on the bearings by caps 34 and 35, the latter seating on the shoulders 25 and 90 26 of the bearing members. Ducts 59 and 60 are provided in the end of the hub adjacent the bearing 20, while ducts 37, 38, 39 and 40 are provided in the other end 95 of the hub. These ducts are formed by drilling openings parallel to the axis of the hub and other openings at right angles to the first-mentioned openings and connecting therewith. This gives a hub that may be easily constructed since it is cylindrical 100 in shape and has all the openings drilled therein extending either parallel to the axis or at right angles to a plane through the axis. Integral with the hub 29 are two cylindrical projections 41 and 42 having 105 threaded openings 43 and 44, respectively, formed therein. Tanks 45 and 46 are mounted on these projections by means of nipples 47 and 48 which engage in the threaded openings 43 and 44, respectively. 110 The ducts formed in the hub 29 are so positioned that they register with the open-

ings formed in the bearings 19 and 20 as the hub is rotated.

Positioned in the tank 45 is a long inlet pipe 49 connected with the duct 39, while 5 located in the tank 46 is a long inlet pipe 51 connected with the duct 38. Short pipes 50 and 61 are located in the tank 45 and connected to the ducts 59 and 37, respectively, while short pipes 52 and 62 are mounted in 10 the tank 46 and connected to the ducts 60 and 40. A by-pass 63 is provided between the ducts 37 and 39 and another by-pass 64 is provided between the ducts 38 and 40.

The operation of the device is as follows:

15 When the tank 46 is in its lower position water is poured into the reservoir 15 and flows downward through pipe 56, opening 28, duct 38 and pipe 51 into the tank 46. Air is forced up through the pipe 62, duct 40, 20 by-pass 30, duct 39, by-pass 63 and pipe 49 into the tank 45. The tanks are then rotated about the bearings 19 and 20, positioning the tank 46 above the tank 45. Water now flows from the reservoir, through pipe 56, opening 28, duct 38, pipe 49 into the tank 45. The air passes upward from the tank 45, through pipe 61, duct 37, by-pass 30, duct 38, by-pass 64 and pipe 51 into the tank 46. The water continues to flow into tank 45 30 until the air in tank 46 is compressed by a pressure equal to the head of water. This pressure plus the head of water in the tank 46 causes water to flow through pipe 50, duct 59, opening 27, discharge pipe 57 and out 35 through a nozzle formed on the upper end 58 of the pipe 57. By the time the tank 46 has been emptied into the reservoir 15 the tank 45 is filled from the reservoir 15. The tanks are again rotated about the bearings 40 19 and 20, positioning the tank 45 above the tank 46. The tank 46 is now emptied into the reservoir while the tank 45 is filled from the reservoir in the manner described above.

45 I would state in conclusion that while the illustrated example constitutes a practical embodiment of my invention I do not limit myself strictly to the exact details herein illustrated since manifestly the same can be 50 considerably varied without departing from the spirit of the invention as defined in the appended claims.

Claims:

1. A mechanical fountain, comprising a 55 reservoir mounted on a stand, a pair of bearing members having openings therein

carried by the stand, means for connecting one opening extending through the bearing members to the reservoir, a discharge pipe associated with the other opening, a cylindrical hub having ducts therein mounted on the bearings carried by the stand, two tanks attached to opposite sides of said hub, and inlet and outlet pipes located in each tank and registering with the ducts in the hub to register with the openings in the bearing members when the tanks are in vertical position.

2. In a mechanical fountain, a cylindrical hub having ducts therein adapted to be 70 mounted on bearings carried by the fountain frame, said bearings being provided with openings, packing rings associated with the hub for making tight connection between the hub and bearings, tanks mounted on opposite sides of the hub, and inlet and outlet openings located in said tanks and in alignment with the ducts in the hub, said ducts in the hub being so located as to register with the openings in the bearings when the tanks 80 are in vertical position.

3. A mechanical fountain, comprising a reservoir carried by a stand, a pair of bearing members having openings therein provided in conjunction with the stand, means 85 for connecting one of said openings with the reservoir, a discharge pipe connected with another of said openings, a cylindrical hub having a plurality of ducts therein rotatably mounted on said bearings, packing rings associated with said hub for making tight engagement between the hub and bearings, two tanks attached to opposite sides of the hub, and inlet and outlet pipes located in the tanks and mounted to register with the ducts 90 in the hub which register with the openings in the bearing members when the tanks are 95 in vertical position.

4. A mechanical fountain including a reservoir for holding a liquid and a plurality of tanks for receiving the liquid from and delivering it to said reservoir, means for controlling the flow of the liquid comprising a rotatably mounted cylindrical hub carrying said tanks, said hub having a plurality of channels formed therein communicating with the tanks, and a plurality of tubes communicating with said reservoir and co-operating with the hub to establish communication between the tanks and reservoir.
